H. E. STANIFORD.
AUTOMATIC REGISTER GAGE FOR PLATEN PRESSES.
APPLICATION FILED FEB. 24, 1908.

909,249.

Patented Jan. 12, 1909.

UNITED STATES PATENT OFFICE.

HENRY E. STANIFORD, OF SOUTHPORT, CONNECTICUT.

AUTOMATIC REGISTER-GAGE FOR PLATEN-PRESSES.

No. 909,249.

Specification of Letters Patent.

Patented Jan. 12, 1909.

Application filed February 24, 1908. Serial No. 417,310.

To all whom it may concern:

Be it known that I, HENRY E. STANIFORD, a citizen of the United States, residing at Southport, county of Fairfield, State of

5 Connecticut, have invented a new and useful Automatic Registering-Gage for Platen-Presses, of which the following is a specification.

This invention has for its object to provide 10 an automatic registering gage for platen printing presses which shall be simple and inexpensive to produce and may be attached to the press in such a manner as not to interfere in any way with its ordinary 15 use.

With these and other objects in view I have devised the novel automatic gage, of 20 which the following description in connection with the accompanying drawing is a specification, reference characters being used to indicate the several parts.

Figure 1 is a side elevation of the platen and gripper of a printing press, detached, showing the application thereto of my novel 25 automatic registering gage; Fig. 2 a plan view corresponding with Fig. 1; and Fig. 3 is a detail sectional view on the line 3—3 in Fig. 2, looking in the direction of the arrows.

30 10 denotes the platen of a printing press which is provided with arms 11 (one only being shown), by means of which it is pivoted to the bed (not shown) of the press.

12 denotes the gripper shaft which is 35 mounted to oscillate in arms 11, and 13 denotes one of the gripper arms carried by the gripper shaft.

It is of course well understood that in this 40 class of presses, the sheets to be printed are placed upon the platen, the forward edges of the sheets engaging rest pins 14 and one of the side edges resting against a gage pin placed at one side of the platen. As this work is done very rapidly it has heretofore 45 been very difficult, especially in high grade and multiple impression printing, to register the sheets accurately and secure uniform results. This difficulty I wholly overcome by the use of my novel automatic sliding 50 gage, the movement of which is sufficient at each actuation of the press to insure accurate placing of the sheet to be printed.

15 denotes the gage proper, which is a strip of metal having a shank 16 at right 55 angles to the gage. The shank lies under the tympan sheet, that is, between the

platens and the tympan sheet, which is indicated by 17, and the gage itself projects through an opening 18 cut in the tympan sheet.

60

The gage is reciprocated at each actuation of the press by suitable connections, a practical form of which I will now describe. In practice, any number of gages may be provided with shanks of different lengths, the 65 operator using the length of shank best adapted to the size of the form or to the size of the sheets to be printed. The shank of the gage is detachably and adjustably secured to a holder 19 which is itself adjustable on the center-piece 20 of a double crank, the arms 21 of which are provided with lugs 22 which are mounted to oscillate in ears 23 upon an attaching plate 24 which is secured to the side of a platen in any suitable manner, as by screws 25. The holder is made 70 from sheet metal and comprises a substantially U-shaped body 26 which is sprung over the center-piece of the crank and is self-retaining in place but free to slide longitudinally on the center-piece, and a clamp consisting of a plate 27 extending from the body and a clamping plate 28 preferably formed integral with plate 27 which grips and securely locks the shank of the gage between itself and plate 27. In order to 75 doubly insure the forward movement of the gage at each actuation of the press so as to insure the accurate registration of each sheet, the shank of the gage may be provided with a shoulder 29 which is engaged by the metal of the holder at the intersection of the clamping plate with plate 27.

80

30 denotes an operating arm which is shown as formed integral with the crank 95 which is bent to suitable shape and comprises a horizontal portion 31 which has a sliding engagement with an arm 32 detachably secured to the gripper shaft. This arm is shown as provided with a hub 33 which 100 slides on the gripper shaft and is locked in place after adjustment by a set screw 34.

The operation is as follows: At each oscillation of the gripper shaft, arm 32 carried thereby is swung downward and then backward again. The effect of the downward movement of arm 32 is, by means of the operating arm, to swing the crank and with it the holder and gage forward so that the gage will move the sheet to be printed, and which 110 will move against rest pins 14, forward to the determined position, each sheet being

5 moved to exactly the same position, thus insuring perfect accuracy and uniformity in printing the sheets. The return movement of the gripper shaft moves the gage backward again ready for the next sheet. In case it is required to change the position of the gage, it is simply necessary to cut another hole in the tympan sheet. It will of course be understood that gages having different lengths of shanks may be used and that a gage may be adjusted transversely to the platen by simply sliding the holder on the center-piece of the crank. The throw of the gage, that is the amount of its reciprocation, may be regulated by adjustment of arm 32 on the gripper shaft, which is engaged by the operating arm, thereby increasing or diminishing the throw of the crank. When it is not desired to use the gage, it is removed from the holder without disturbing the other parts of the device, which have no effect whatever on the regular operation of the press.

10 Having thus described my invention I 25 claim:

1. A device of the character described comprising a gage adapted to project through a hole in a tympan sheet and having a shank which in use lies under the tympan sheet, a holder comprising a substantially U-shaped body and a clamp for the gage shank and a crank having a center-piece slidably engaged by the U-shaped body of the holder.
2. A device of the character described comprising a gage adapted to project through a hole in a tympan sheet and having a shank which in use lies under the tympan sheet and is provided with a shoulder, a holder having a clamp to receive the shank and which is engaged by said shoulder and a crank having a center-piece which is slidably engaged by the holder.
3. A device of the character described comprising a gage adapted to project through a hole in a tympan sheet and having a shank

which in use lies under the tympan sheet, a holder having a clamp engaged by said shank, a crank having a center-piece on which the holder may slide and arms provided with lugs and an attaching plate having ears in which said lugs are mounted to oscillate. 50

4. A device of the character described comprising a gage adapted to project through a hole in a tympan sheet and having a shank which in use lies under the tympan sheet, a holder having a clamp which is engaged by said shank and a crank having a center-piece on which the holder may slide and an operating arm by which the crank is oscillated and the gage reciprocated. 60

5. In a press of the character described, the combination with a gripper shaft having an adjustable arm extending therefrom and a tympan sheet having a hole, of a gage projecting through the hole in the tympan sheet and having a shank lying under said sheet, a holder with which said shank is engaged and a crank having a center-piece upon which the holder may slide and an operating arm which slidably engages the arm on the gripper shaft. 65

6. In a press of the character described, the combination with a gripper shaft having an arm extending therefrom and a tympan sheet having a hole, of a gage projecting through the hole in the tympan sheet and having a shank lying under the tympan sheet, an attaching plate having ears, a crank mounted to oscillate in said ears and 75 having an operating arm and a center-piece and a holder which slidably engages said center-piece and is provided with a clamp which receives the shank of the gage. 80

In testimony whereof I affix my signature, 85 in presence of two witnesses.

HENRY E. STANIFORD.
